US00D721702S

(12) **United States Design Patent**
Lee et al.

(10) **Patent No.:** US D721,702 S
(45) **Date of Patent:** ** Jan. 27, 2015

(54) **KEYBOARD**

(71) Applicant: **Samsung Electronics Co., Ltd.**,
Suwon-Si (KR)

(72) Inventors: **Hyun-Il Lee**, Seocho-gu (KR);
Young-Geun Lim, Anyang-Si (KR);
Beom-Soo Bae, Anyang-Si (KR);
Bong-Gun Kim, Seocho-gu (KR)

(73) Assignee: **Samsung Electronics Co., Ltd.**,
Suwon-Si (KR)

(**) Term: **14 Years**

(21) Appl. No.: **29/460,680**

(22) Filed: **Jul. 12, 2013**

(30) **Foreign Application Priority Data**

Jan. 30, 2013 (KR) 30-2013-005119

(51) **LOC (10) Cl.** 14-02

(52) **U.S. Cl.**

USPC **D14/392**

(57) **CLAIM**

The ornamental design for a keyboard, as shown and described.

DESCRIPTION

FIG. 1 is a top front perspective view of a keyboard showing our new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is an enlarged detail view of the portion A encircled in FIG. 2;

FIG. 9 is a cross-sectional view thereof taken along line 9-9 in FIG. 8; and,

FIG. 10 is another front view thereof being mounted on a portable computer.

The broken lines illustrating portions of the keyboard are for environmental purposes only and form no part of the claimed design.

1 Claim, 5 Drawing Sheets
